UNITED STATES PATENT OFFICE.

EDWARD M. HEWLETT AND WALDO W. WILLARD, OF SCHENECTADY, NEW YORK, AS
SIGNORS TO GENERAL ELECTRIC COMPANY, A CORPORATION OF NEW YORK.

RESILIENT SUPPORT.

Application filed May 21, 1924. Serial No. 714,944.

To all whom it may concern:

Be it known that we, EDWARD M. HEWLETT and WALDO W. WILLARD, citizens of the United States, residing at Schenectady, 5 in the county of Schenectady, State of New York, have invented certain new and useful Improvements in Resilient Supports, of which the following is a specification.

Our invention relates to resilient supports 10 and has for its object the provision of supporting means whereby the supported body is protected from shocks from all directions and while being maintained normally in a definite position.

More specifically our invention relates to 15 a resilient support particularly adapted for instruments of precision by means of which the instrument is resiliently supported to provided for independent movement of the 20 instrument with relation to its mount as a protection from shocks, while being returned thereafter accurately to a definite position of initial adjustment. In carrying out our invention we provide a cone-shaped 25 position defining member and a member resiliently seated on this cone-shaped member. One of these members is attached to the mount while the other is attached to the supported body.

For a more complete understanding of 30 our invention, reference should be had to the accompanying drawing in which Fig. 1 is an elevation view in section of a resilient support embodying our invention, 35 while Fig. 2 is an elevation view on a reduced scale showing the application of our invention to an instrument of precision.

Referring to Fig. 1 of the drawing, in 40 carrying out our invention in one form as applied to the hanging of a supported body 10 on a supporting body or mount 11, we provide a pin or rod 12 which is suitably secured to the supporting body 11 so as to extend downward therefrom and normally 45 be in a substantially vertical position. The pin 12 may be and is shown as secured to the body 11 by threading it and screwing it into cooperating threads in the supporting body. The pin is provided with an 50 enlarged base portion 13 which is seated in a depression 14 formed for it in the body 11. To prevent turning and consequently loosening of the pin, grooves 15 extending lengthwise of the pin are provided in the 55 portion 13 and the metal of the body 11 is

peened over into these grooves 15, as shown at 16.

The lower end of the enlarged portion 13 is provided with a suitably shaped position defining surface 17, shown as being 60 cone-shaped, having its axis coincident with the longitudinal axis of pin 12. On the cone-shaped surface 17 is seated a sleeve 18, the upper end of the sleeve 18 being 65 shaped in conformity with the surface 17. 65 The sleeve 18, when properly seated, is concentric with the pin 12. On the upper end of the sleeve 18 is a flange 19 which has a close sliding fit in an outer sleeve 20 secured to the supported body 10. An internal flange 21 is provided in the upper 70 end of sleeve 20 against which flange 19 is held by a helical spring 22, the lower end of which rests on an internal flange 25 secured to the lower end of sleeve 20. 75 As shown, the flange 25 is in the form of a screw plug which is screwed into the lower end of sleeve 20, suitable threads being provided. A central aperture 26 is provided in the plug 25 through which the 80 sleeve 18 extends and in which the sleeve has a close sliding fit. Bearing against the lower face of plug 25 is a helical spring 27, the lower end of which is seated on a washer 28 which in turn rests against nuts 85 29 on the lower end of pin 12. As shown, the plug 25 may be provided with suitable recess or depression 30 to receive the end of spring 27 and to provide a seat for it.

The spring 27 is slightly larger in diameter than the sleeve 18 so that the sleeve is free to move axially of the spring 27 without touching it. It will be observed that the spring 27 acts against the spring 22 tending to compress it, but the spring 22 95 is made considerably stronger than the spring 27 and hence is not compressed thereby.

As shown, the sleeve 20 may be provided 100 with external threads 31 and secured to the supported member 10 by screwing it into cooperating threads 32 on the supported member. A set screw 33 may be provided in member 10 to lock the sleeve 20 in adjusted position. The supported member 10 105 may be leveled or otherwise adjusted by loosening screw 33 and turning sleeve 20 in the proper direction.

It is contemplated that a plurality of 110 spring supports of the type shown in Fig.

1 will be used in supporting an instrument of precision. As applied to a periscopic sighting instrument 35 hung from an overhead supporting wall 36 (Fig. 2), three 5 spring supports 37, 38 and 39 may be used, these supports being spaced at equal distances about the device 35.

In the event that sudden shocks are applied to the supporting body 11, the springs 10 22 and 27 will yield to absorb the shocks and thus prevent injury of the instrument 35, the spring 22 absorbing shocks applied to the supporting body in a downward direction and the spring 27 absorbing shocks 15 applied to the supporting body in an upward direction. One of the functions of the cone-shaped seat 17 is to cause a component of shocks having a lateral direction to be applied to the spring 22 and thereby 20 be absorbed. Thus, in case a lateral shock, or any lateral component of a shock, is applied to the supporting body 11, the pin 12 will be displaced laterally with relation to the sleeve 18 due to the inertia of the supported body 10. As this displacement takes 25 place, it will be observed that the sleeve 18 will be forced downward by reason of the inclined conic bearing surfaces between the sleeve and pin, whereby spring 22 will be compressed. After the energy of the shock 30 has been dissipated the sleeve 18 returns to its original position which is defined by its cone-shaped seat. The position of the supported body is thus definitely defined in a 35 lateral direction. In a vertical direction the position of the supported body is defined by the seating of sleeve 18 on flange 21.

While we have described our invention as embodied in concrete form and as operating 40 in a specific manner in accordance with the provisions of the patent statutes, it should be understood that we do not limit our invention thereto since various modifications thereof will suggest themselves to those skilled in the art without departing from the spirit of our invention, the scope of which is set forth in the annexed claims.

What we claim as new and desire to secure by Letters Patent of the United States, 50 is,

1. A resilient support comprising two members carried by the supported and supporting bodies respectively, and resilient means for holding said members in engagement, the cooperating bearing surfaces of said members being inclined with respect to the direction of the force applied by said resilient means, whereby lateral shocks are applied to said resilient means.

2. A resilient support comprising two members carried by the supported and supporting bodies respectively, and resilient means for holding said members in engagement, the cooperating bearing surfaces of

said members being beveled, whereby lateral 65 shocks are applied to said resilient means.

3. A resilient support comprising two members carried by the supported and supporting bodies respectively, one of said members being provided with a cone-shaped 70 seat for the other member, and resilient means for holding said members in engagement, whereby lateral shocks are applied to said resilient means.

4. A resilient support comprising two members provided with inclined cooperating bearing surfaces, a connection between one of said members and the supporting body, a yieldable connection between the other member and the supported body, and resilient 75 means carried by said first member acting on the supported body so as to hold said inclined surfaces in engagement and absorb shock causing lateral displacement thereof.

5. A resilient support comprising two members provided with cone-shaped cooperating bearing surfaces, a connection between one of said members and the supporting body, a seat on the supported body for the other member, a spring for holding said second member to said seat, and a second spring carried by said first member acting on said supported body in opposition to said first spring so as to hold said members in 90 engagement.

6. A resilient support comprising a pin depending from the supporting body provided with a cone-shaped portion, a sleeve carried by the supported body cooperating with said cone-shaped portion, and a spring on said pin acting on said supported body so as to hold said sleeve seated on said cone-shaped portion.

7. A resilient support comprising a pin depending from the supporting body provided with a cone-shaped portion, a sleeve on said pin cooperating with said cone-shaped portion resiliently mounted on the supported body, and a spring on said pin acting on the supported body so as to hold said sleeve seated on said cone-shaped portion.

8. A resilient support comprising a pin depending from the supporting body provided with a cone-shaped portion, a sleeve member encircling said pin cooperating with said cone-shaped portion, a seat for said sleeve member on the supported body, a spring for holding said sleeve on said seat, and a second spring on said pin acting on said supported body in opposition to said first spring so as to hold said sleeve member in engagement with said cone-shaped portion.

In witness whereof, we have hereunto set 125 our hands this 20th day of May, 1924.

EDWARD M. HEWLETT.
WALDO W. WILLARD.
